ELECTRICAL APPARATUS

James W. Jacobs, Dayton, Ohio, assignor to General Motors Corporation, Dayton, Ohio, a corporation of Delaware

Application August 12, 1952, Serial No. 303,977

4 Claims. (Cl. 200—83)

This invention relates to an electrical apparatus and more particularly to switches and controls.

Experience has shown that the life of the bellows or diaphragm is greatly reduced in controls wherein the switch mechanism is directly connected to the actuated bellows or diaphragm, and a high force snap-action toggle mechanism is directly applied to the connection to provide a wide differential. I have found that the shock and vibration upon the bellows or diaphragm is so great as to set up a shock wave causing a whole series of vibrations.

It is an object of my invention to so arrange such a switch that the life of its bellows is increased and the shock on the bellows is greatly reduced.

It is another object of my invention to so arrange such a switch that the bellows is isolated from the shock taking place in the switch.

It is another object of my invention to so arrange such a switch that a lost motion connection connects the bellows and the switch contact mechanism to reduce the transmission of shock and vibration and yet provide an accurate relationship between the pressure in the bellows and the operation of the switch contact mechanism.

These objects are attained by this invention, one form of which is disclosed herein. In the form disclosed, an adjustable mounted bellows and a switch contact mechanism are mounted within a frame. A member connected to the switch contact mechanism has the adjacent ends of two toggle blades pivotally connected thereto. These blades are column loaded by a folded over leaf spring. An adjustable stop associated with the member connected to the switch mechanism locates the open position of the switch while a rotatable cam stops the connecting member in various positions to locate the closed position of the switch contact mechanism and the toggle blades. To prevent the transmission of shock to the bellows when the toggle mechanism forces the connection against a stop in either direction there is provided a lost motion connection between the bellows follower and the connecting member.

Further objects and advantages of the present invention will be apparent from the following description, reference being had to the accompanying drawings wherein a preferred form of the invention is clearly shown.

In the drawing:

Figure 1 is a view partly in section taken substantially along the line 1—1 of Figure 2;

Figure 2 is a sectional view taken substantially along the line 2—2 of Figure 1;

Figure 3 is a fragmentary view similar to a portion of Figure 1 showing the start of the opening movement of the switch mechanism with the bellows pulling down;

Figure 4 is a fragmentary view somewhat similar to Figure 3 with the toggle mechanism shown in its position at the end of the opening movement of the switch contact mechanism and with the bellows pulling down; and

Figure 5 is a view similar to Figures 3 and 4 with the parts shown in the position they assume during the middle of the switch closing movement with the bellows pushing up.

Referring now to the drawings and more particularly to Figure 1 for a disclosure of one form of my invention, there is shown a U-shaped metal frame 20 having a switch contact and terminal member 22 of electrical insulating material located between and connected by the

screws 23 to the two legs of the frame. Extending through the terminal member 22 are two terminal posts 24 and 26. The inner end of the terminal post 26 has connected to it a thin bent leaf spring contact carrying member 28 having a movement contact 30 fastened to its free end. The adjustable terminal post 24 carries the stationary contact 32.

The operating connection with the contacting carrying member 28 is made by a member 50 of some suitable electrical insulating material. This member 50 has a slot 52 which engages the opposite sides of the member 28 as shown in Figure 2. Alongside of the lower portion of the member 50 is a connecting member 48 of metal. This metal member 48 on its opposite faces is provided with sets of notches which receive the adjacent chisel-shaped ends of the toggle blades or links 56 and 58. The opposite chisel-shaped end of the toggle blade 58 rests in a notch in a bearing member 60. This bearing member 60 is rotatably mounted within the inner end of an adjusting screw 62 threaded through the leg of the frame 20. The opposite chisel-shaped end of the toggle blade 56 rests within a notch in a folded over leaf spring 64 having its folded over portion provided with a pad 76 resting against the adjacent portion of the U-shaped frame 20.

The lower end of this spring 64 is provided with a threaded bushing 67. A screw 70 threads through the bottom portion of the U-shaped frame member 20 into the threaded bushing. A compression type coil spring 72 extends between the bottom of the frame 20 and a shoulder upon the lower end of the spring 64. This coil spring 72 tends to urge the leaf spring 64 upwardly while the screw 70 limits this upward movement and thus adjusts the vertical position of the spring 64. The vertical position of the spring 64 adjusts the angularity of the toggle blade 56. The column loading of the toggle blades 56 and 58 is determined by the adjustment of the screw 62 which determines the force which will be applied by the spring 64 to the toggle blades 56 and 58. This determines the pressure or temperature difference between the opening and closing of the switch contacts.

The switch opening movement of the contacts 30 and 32 is limited by a large flat headed adjustable screw 94 which is threaded into the boss 95 extending downwardly from the terminal member 22. The head of this screw 94 is engaged by a projection 96 extending from the member 48 beneath the head of the screw 94.

The member 48 has a cutout portion providing connecting legs 150 and 151. These connecting legs 150 and 151 extend on opposite sides of a camshaft 88 which is rotatably mounted in the sides of the U-shaped frame 20. These legs 150 and 151 connect directly with the horizontal yoke 153, a portion of which serves as a follower for the cam 86 which is fastened to the camshaft 88. The cam 86 has its periphery arranged in the shape of a spiral with a large nose 87 extending from the periphery between the beginning and the end of the spiral. The camshaft 88 may be rotated to various angular positions to present different positions of its periphery to the yoke 153 for serving as an adjustable stop to determine the location of the members 48 and 50 when the contacts 30 and 32 are in engagement. This determines the switch opening temperature or pressure.

When a wide differential is desired between the opening and closing point of the switch, the column loading upon the toggle blades 56 and 58 is quite high. This causes a considerable shock when the projection 96 engages the head of the screw 94 and likewise there is a considerable shock when the yoke portion 153 engages the periphery of the cam 86. It was found when the actuating bellows or diaphragm was connected directly to the yoke 153 that a severe shock was transmitted to the actuating bellows or diaphragm. This caused the bellows or diaphragm to set up a wave which generates a number of vibrations in the bellows or diaphragm. Since the bellows or diaphragm must be made of spring material which is relatively hard they are subject to fatigue breakage. These vibrations greatly increased the number of flexings of the bellows or diaphragm for each opening and closing of the switch mechanism. This

made the life of the bellows or diaphragm very short when a wide differential was required.

As shown in Figure 1 in the lower portion of the frame 20 is a flexible metal actuating bellows 38. The lower end of this bellows is connected to a capillary tube 40 which may extend to a source of varying fluid pressure such as a thermostatic bulb. Rotatably mounted upon the capillary tube 40 is a hollow screw 92 which threaded into the yoke portion of the frame 20. By rotating this screw 92 the lower end of the bellows 38 may be raised or lowered. This changes both the opening and closing temperatures of the switch.

Instead of directly connecting the bellows 38 to the yoke 153, I provide a separate bellows follower 139. This bellows follower 139 has a pair of feet 141 fastened to the top of the bellows 38. One of the feet is provided with an upwardly extending projection 143 extending through an aperture in the yoke 153. The follower 139 is also provided with a lost motion slot 145. (See Figure 3) extending through this slot 145 is a rivet 149. The shank of this rivet 149 has a large diameter portion in the slot 145 and a smaller diameter portion extending through apertures in the members 48 and 50. The members 48 and 50 are tightly clamped between the rivet head and the shoulder formed by the larger diameter shank portion of the rivet while the opposite end of the rivet is likewise formed with a head to hold the follower 139 in sliding engagement with the adjacent side of the connecting member 48. This slideable lost motion connection is therefore made by the rivet 149 with the lower end of the sliding connection being guided by the sliding projection 143 upon the member 139 which extends through a slot in the yoke portion 153 at the bottom of the member 48.

Figure 1 shows the switch mechanism immediately after the bellows 38 has moved the switch contact mechanism 28 to the closed position. The yoke 153 rests against the periphery of the cam 86. The rivet 149 is in the middle of the slot 145 so that when the yoke engaged the cam 86 the bellows 38 was disconnected from the member 48 so that no shock could be transmitted to the bellows 38.

To move the switch mechanism 28 to the open position, the pressure within the bellows 38 is lowered and when the bellows 38 is collapsed sufficiently the upper end of the slot 145 will engage the rivet 149 to move the members 48, 50 and 28 downwardly. This movement takes place rapidly with the toggle blades 56 and 58 providing a snap-action movement to minimize arcing of the contacts 30 and 32. The toggle blades 56 and 58 are approximately in the dead center position in Figure 3.

As soon as the blades pass the dead center position they, along with the members 48, 50 and 28, will snap to their lowermost position with the projection 96 engaging the head of the screw 94 as shown in Figure 4. In this movement the rivet 149 will move away from the upper end of the slot to the middle portion where it is shown in Figure 4 as the projection 96 engages the head of the screw 94. Therefore, when this engagement takes place the bellows 38 and its follower 139 will be disconnected from the members 48 and 50 to which the shock is applied. Since the bellows 38 is disconnected from the member 48 when the shock occurs, the bellows does not receive the shock and does not receive the severe vibrations which followed the shock when the bellows was directly connected to the toggle mechanism. In this way the life of the bellows was increased more than 100 times.

The return or closing movement of the bellows is shown in Figure 5. The bellows 38 and its follower 139 move upwardly until the bottom of the slot 145 engages the rivet 149. Further upward movement moves the members 48, 50 and 28 as well as the toggle blades 56 and 58 until the toggle blades 56 and 58 cross the dead center position as shown in Figure 5. From this point the

toggle blades 56 and 58 as well as the members 48, 50 and 28 move directly to the position shown in Figure 1 without further movement of the bellows 38. During this latter movement the rivet 149 moves away from the end of the slot to the position shown in Figure 1 so that at the time of the shock when the yoke 153 strikes the periphery of the cam 86, the bellows 38 is disconnected and does not suffer the shock.

In this arrangement therefore the bellows is protected from shock created when a high force toggle snap-action mechanism is used to achieve a wide differential.

While the form of embodiment of the invention as herein disclosed constitutes a preferred form, it is to be understood that other forms might be adopted as may come within the scope of the claims which follow.

What is claimed is as follows:

1. A control including an actuating diaphragm means, a control device movable to and from a control position, a toggle snap-action device directly connected to the control device for causing the control device to move with a snap action, a stop arrangement for limiting the movement of the control device, and a freely movable limited lost motion connection connecting said diaphragm means and said control device, said stop arrangement including a rotatable cam shaft provided with a rotary cam, said control device having a stop portion extending into cooperating relationship with said rotary cam for limiting the movement of the control device in one direction.

2. A control including an actuating diaphragm means, a control device movable to and from a control position, a toggle snap-action device directly connected to the control device for causing the control device to move with a snap action, a stop arrangement for limiting the movement of the control device, and a freely movable limited lost motion connection connecting said diaphragm means and said control device, said stop arrangement including a rotatable cam shaft provided with a rotary cam, said control device having a portion extending around the cam and having a stop portion on one side extending into cooperating relationship with said rotary cam for limiting the movement of the control device in one direction.

3. A control including a control device movable to and from a control position, an actuating diaphragm means having an axis along which its principal movement takes place, a follower extending along said axis connected to a movable portion of said diaphragm means, a connector extending along said axis in sliding engagement with said follower and connected to said control device, toggle means connected directly to said connector, adjustable stop means for limiting the movement of said connector along said axis in either direction, and a pin and slot type lost motion connection between said connector and said follower.

4. A control including a control device movable to and from a control position, an actuating diaphragm means having an axis along which its principal movement takes place, a follower extending along said axis connected to a movable portion of said diaphragm means, a connector extending along said axis in sliding engagement with said follower and connected to said control device, toggle means connected directly to said connector, adjustable stop means for limiting the movement of said connector along said axis in either direction, and a pin and slot type lost motion connection between said connector and said follower, and a sliding bearing between said connector and said follower spaced from said lost motion connection.
